UNITED STATES PATENT OFFICE.

STERLING H. CAMPBELL, OF ST. LOUIS, MISSOURI, ASSIGNOR TO WESTERN RAILWAY EQUIPMENT COMPANY, OF ST. LOUIS, MISSOURI, A CORPORATION OF MISSOURI.

DRAFT GEAR.

Application filed September 26, 1925. Serial No. 58,692.

My invention relates to draft gear for railway cars and particularly to means for limiting the movement of the draft key in the direction of its length. This I accomplish by situating in the path of the key a stop plate provided with an opening for the insertion and removal of the key and a closure for the opening.

In the accompanying drawings, which illustrate two forms of draft gear made in accordance with my invention, Figure 1 is a horizontal section; Figure 2 is a side view; Figure 3 is a section taken on the line 3—3 of Figure 1; Figure 4 is an enlarged perspective view of the stop plate; Figure 5 is a view similar to Figure 3 but showing a modification; Figure 6 is a section taken on the line 6—6 of Figure 5; and Figure 7 is a side view of the form of gear shown in Figures 5 and 6.

Referring first to Figures 1 to 4 inclusive, 10 indicates draft sills preferably formed of channel bars and spaced apart by a top plate 11. Situated between the sills are the draft yoke 12 and coupler shank 13 through which passes the draft key 14. Secured to the outer faces of the sill webs are cheek pieces 15 in which are formed slots 16 for the reception of the ends of the key 14, which key has 20 formed on one end a head 17. Secured to the flanges of the sill adjacent to the headed end of the key is a stop plate 18 having a central opening 19 for the insertion and removal of the key. After the key has been 30 placed in position the opening 19 is stopped by a closure piece 20, shown in detail in Figure 4, which closure piece is provided with fingers 21 adapted to project through the opening and be bent over to retain the piece 40 in place.

In the form of draft gear above described the cheek pieces 15 are extended toward the rear and provided with a second pair of slots for the reception of a second draft key 22.

45 Figures 5, 6 and 7 show a modification in which the cheek pieces 15 are replaced by cheek pieces 23 secured to the inside faces of the sills and provided with stops 24 for a follower plate 25. The principal difference, 50 however, in relation to the present invention lies in the fact that a stop plate 26 is secured to only one flange of the sill, the upper edge being provided with a notch or re-

cess 27 equivalent to the opening 18 in the previous form. This recess is stopped by a 55 closure piece 28 having a turned over edge 29 and secured in position by a bolt 30.

Having fully described my invention, what I claim as new and desire to secure by Letters Patent of the United States is:

1. In a device of the class described, the combination with a pair of draft sills, of a draft key passing through said sills, a stop plate arranged in the path of said key, said plate being provided with an opening for the insertion and removal of the key, and a closure piece for said opening.

2. In a device of the class described, the combination with a pair of draft sills, of a draft key passing through said sills, a stop plate carried by one of said sills and arranged in the path of said key, said plate being provided with an opening for the insertion and removal of said key, and a closure piece for said opening.

3. In a device of the class described, the combination with a pair of draft sills, of a draft key passing through said sills, a stop plate secured at both its upper and lower edges to one of said sills, said plate being provided with an opening for the insertion and removal of the key, and a closure piece for said opening.

4. In a device of the class described, the combination with a pair of draft sills, of a draft key passing through said sills, a stop plate carried by one of said sills and arranged in the path of the key, said plate being provided with an opening for the insertion and removal of the key, and a closure piece for said opening having fingers adapted to be bent into locking contact with the stop plate.

5. In car construction having slotted draft sills for the reception of a transversely extending connecting key such as in a draft rigging, an attachment for preventing withdrawal of such key in one direction, said attachment comprising a member adapted to be supported from the corresponding adjacent draft sill, and a second member removably secured to the first member and disposed opposite the end of such key.

In testimony whereof, I hereunto affix my signature, this 23rd day of September, 1925.

STERLING H. CAMPBELL.
